UNITED STATES PATENT OFFICE.

OSCAR JUNGGREN, OF SCHENECTADY, NEW YORK, ASSIGNOR TO GENERAL ELECTRIC COMPANY, A CORPORATION OF NEW YORK.

ELASTIC-FLUID TURBINE.

No. 845,710.

Specification of Letters Patent.

Patented Feb. 26, 1907.

Application filed September 24, 1904. Serial No. 225,748.

To all whom it may concern:

Be it known that I, OSCAR JUNGGREN, a citizen of the United States, residing at Schenectady, county of Schenectady, State of New York, have invented certain new and useful Improvements in Elastic-Fluid Turbines, of which the following is a specification.

This invention relates to turbine-engines driven by steam or other elastic fluid; and its object is to provide a construction of bucket-wheels which eliminates the end thrust on the shaft and increases the capacity of the machine.

With some shapes of buckets there is little or no end thrust on the shaft, so that if the turbine is a vertical one the lubricant-pressure on the step-bearing is substantially the same whether the engine is running or not; but if the steam has a low velocity and the speed of the wheel is high the shape which the buckets must have in order to extract the proper amount of energy is such that an appreciable end thrust is set up. In order to overcome this, I provide each wheel with two similar sets of buckets and place between them double nozzles adapted to deliver steam in opposite directions transverse to the plane of rotation, so that the end thrust on the shaft due to one set of buckets is balanced by that due to the other set. In a turbine having a plurality of stages the end thrust is liable to be considerable, and its entire elimination is especially important. Since many engineers believe that the best practice is to use only a single row of buckets in each stage, I dispense with those additional wheel-buckets and stationary intermediates frequently used, so that there is but a single expansion of steam in each stage; but by using double nozzles and two oppositely-disposed sets of buckets the torque of each wheel is doubled. This is an important point, because the capacity of a turbine is determined by the number of nozzles that can be distributed around the circumference of the lowest-stage diaphragm. Substantially the entire circumference is occupied by nozzles. In the other stages the number is less, diminishing toward the high-pressure stage.

My invention enables me to practically double the capacity of the machine.

The invention can be carried out in various ways and is applicable to both vertical

and horizontal turbines. For the sake of convenience I shall describe it as embodied in an upright machine.

In the accompanying drawings, Figure 1 is a top plan view of an upright steam-turbine containing my invention. Fig. 2 is a half-diametrical vertical section of the same on a larger scale. Figs. 3 and 4 are vertical sections showing modifications, and Fig. 5 is a cross-section of a nozzle.

The turbine shown in all the figures is a four-stage, single-wheel-per-stage machine; but it is to be understood that the number of stages can be varied. It comprises four bucket-wheels 1 2 3 4, all mounted on an upright shaft 5 and revolving in a stationary casing 6, which is divided into chambers or stages by stationary partitions or diaphragms 7 between the wheels. The casing is closed by a top 8, but is open at the bottom to permit the exhaust-steam to pass freely to a conduit 9, leading to the atmosphere or to a condenser, as desired.

In the structure shown in Fig. 1 the steam from the upper row of buckets exhausts by passing downwardly through the spaces between the wheel-spokes to the conduit 9. In Figs. 3 and 4 the steam from the upper buckets of the lower wheel exhausts to the conduit 9 through passages formed in the casing.

At a suitable point or points above the first stage is or are located a steam chest or chests 10, in which are valves 11, that admit live steam to the nozzles 12, which deliver it to the first-stage wheel. The nozzles are formed in the top and bottom of the horizontal arm of one or more hollow castings 13, which communicate with their respective steam-chests and receive the steam which passes the valves. In Fig. 2 this casting is shown as L-shaped, owing to the location of the steam-chest. The structure forms a double set of nozzles, which deliver the steam obliquely upward and downward to two parallel rows of buckets 14, secured to the wheel 1. Each of the two sets of nozzles from which the steam is simultaneously discharged effects a single expansion of the steam. In like manner the bucket-wheels 2, 3, and 4 each have two rows of buckets, between which one or more hollow castings 15 extend, containing two sets of nozzles 16, like those in the casting 13. The castings 15 are se-

cured to the inside of the casing 6, and each communicates with the preceding stage, preferably by means of a large pipe 17, located outside of the casing. The pipes may be connected with the upper stage at one point only, as shown in Fig. 2, or at two or more points, as shown in Fig. 4. They preferably have a horizontal header 18, opening by a long horizontal slot into a horizontal chamber 19, which communicates with the nozzle-casting. This insures an even distribution of the steam to all the nozzles. The pipes drop below the headers to trap the water of condensation and have drain-pipes 20 at their lower ends. Instead of using pipes attached to the casing there may be passage ways 21 cored out in the walls of the casing and connecting each upper stage with the nozzle-casting of the next lower stage, as shown in Fig. 3.

By test it has been demonstrated that bucket-wheels of large diameter are distorted when subjected to different temperatures on opposite sides. By placing a nozzle 25 between the rows of wheel-buckets and discharging motive fluid therefrom in opposite directions the tendency of one part to distort is counteracted by an equal and opposite tendency of another part.

30 Each partition or diaphragm is provided with a cylindrical projection or enlargement 22, located in close proximity to the bucket-wheel and coöperating therewith to reduce the rotation losses by presenting a smooth 35 surface to the wheel. The projections also tend to confine the exhaust motive fluid to the chamber located around it. To state the matter differently, the space between a projection and the adjacent wheel is restricted, 40 while the conduits leading to the next stage of lower pressure are large. Hence the exhaust fluid will freely pass through them. These cylindrical projections have the further advantage of preventing cross-currents of motive fluid from one nozzle or set of nozzles to another nozzle or set of nozzles located at a 45 point or points angularly displaced. For example, assume that a given stage is provided with two nozzles located at diametrically opposite points. Then these cylindrical projections will prevent the column of steam discharged from one wheel from flowing wholly or in part directly across the flat surfaces of the wheel to the opposite nozzle and creating 55 objectionable eddies which decrease the efficiency of the machine. These cylindrical projections are useful whatever the character of the nozzles employed. The projections are separated from the wheel by a clearance 60 which is preferably slightly less than the clearance between the nozzles and moving buckets, so that rubbing of the parts due to any cause is confined to those which are rugged in character. In the present embodiment of the invention it will be noted that 65

the smooth end surfaces of the projections are located in close proximity to the bases of the buckets as distinguished from placing them in close proximity to the sharpened edges of the buckets. Hence any rubbing will 70 not damage the buckets. In addition to the above these walls coöperate with the inner wall of the wheel-casing to form annular chambers and assist in directing the steam exhausting from a wheel into the passages or 75 conduits that convey it to a stage of lower pressure.

In accordance with the provisions of the patent statutes I have described the principle of operation of my invention, together 8c with the apparatus which I now consider to represent the best embodiment thereof; but I desire to have it understood that the apparatus shown is only illustrative and that the invention can be carried out by other means. 85

What I claim as new, and desire to secure by Letters Patent of the United States, is—

1. In an elastic-fluid turbine having a plurality of stages, the combination with a plurality of bucket-wheels each provided with 90 oppositely-disposed rows of buckets, of nozzles extending between said rows and discharging in opposite directions, and wheel-chambers that are common to the rows of buckets mounted on the same wheel. 95

2. In an elastic-fluid turbine having a plurality of stages, the combination with a plurality of bucket-wheels each provided with oppositely-disposed rows of buckets, a chamber that is common to the fluid exhausting 100 from each of the oppositely-disposed rows of buckets, of nozzles extending between said rows and discharging in opposite directions, and conduits for conveying elastic fluid from each chamber to the nozzles of the next lower 105 stage.

3. In an elastic-fluid turbine having a plurality of stages, the combination with a plurality of bucket-wheels each provided with oppositely-disposed rows of buckets, of nozzles extending between said rows and discharging in opposite directions, a casing for 110 said turbine, and passage-ways in the walls of said casing connecting each stage with the nozzles of the next lower stage. 115

4. In an elastic-fluid turbine, the combination of a casing, diaphragms which divide the casing into compartments, a bucket-wheel in each compartment provided with oppositely-disposed rows of buckets, one or more double nozzles for each wheel extending between the 120 said rows of buckets, and cylindrical walls which coöperate with the walls of the casing to form chambers into which the buckets discharge. 125

5. In an elastic-fluid turbine having a plurality of stages, the combination with a plurality of bucket-wheels each provided with oppositely-disposed rows of buckets, of one or more nozzle-castings for each wheel ex- 130

tending between said rows of buckets and having two sets of nozzles discharging in opposite directions.

6. In an elastic-fluid turbine having a plurality of stages, the combination with a casing, diaphragms for dividing the casing into compartments, a plurality of wheels each provided with oppositely-disposed rows of buckets, of nozzles extending between said rows and discharging in opposite directions, and conduits for conveying elastic fluid around the diaphragms from one stage to the nozzles of the next lower stage, the conduits extending transverse to the plane of revolution of said wheel.

7. In an elastic-fluid turbine, the combination with a casing having a top, of a steam-chest mounted thereon, valved ports in the bottom of said steam-chest, an L-shaped hollow casting located inside the casing and communicating with said ports, oppositely-discharging nozzles in the top and bottom of the horizontal arm of said casting, and a bucket-wheel having two rows of buckets revolving respectively above and below said arm.

8. In an elastic-fluid turbine, the combination of a casing, partitions for dividing the casing into stages, a wheel for each stage having rows of buckets, and nozzles for the stages which occupy positions between the rows of wheel-buckets, and a chamber for each stage that is common to the buckets on each wheel.

9. In an elastic-fluid turbine operating by stage expansion, the combination of bucket-wheels for the stages, a nozzle for each stage which is located between rows of buckets on the wheel and discharges in opposite directions to prevent wheel distortion due to unequal temperatures, and a chamber that is common to the rows of buckets on each wheel.

10. In an elastic-fluid turbine, the combination of a casing, a partition for dividing the casing into stages, the partition being provided with an enlargement having a smooth surface, a bucket-wheel located in one of the stages and running in close proximity to the projection to reduce rotation losses, and a nozzle for discharging motive fluid to the wheel.

11. In an elastic-fluid turbine, the combination of a casing, diaphragms which divide the casings into compartments, a bucket-wheel in each compartment provided with oppositely-disposed rows of buckets, one or more double nozzles for each wheel extend-

ing between the said rows of buckets, an annular chamber that is common to the rows of buckets on each of the wheels, and conduits or passages that connect the successive annular chambers with the nozzle of a stage of lower pressure.

12. In an elastic-fluid turbine, the combination of a casing, a bucket-wheel rotating therein, fluid-discharging devices, an annular wall located within the casing and separated from the buckets by a small clearance for preventing cross-currents of motive fluid, and an annular chamber which receives the exhaust from one set of buckets.

13. In an elastic-fluid turbine, the combination of a casing, a bucket-wheel rotating therein, fluid-discharging devices, and a cylindrical wall interposed between the inner wall of the casing and the wheel-axis for preventing cross-currents of motive fluid.

14. In an elastic-fluid turbine, the combination of a casing, a partition for dividing the casing into compartments, wheel-buckets located in the compartments, a shaft for the wheels, fluid-discharging devices, an annular wall interposed between the casing and the shaft and in close proximity to the wheel-buckets to prevent motive fluid from flowing across the surface of the wheel.

15. In an elastic-fluid turbine, the combination of a casing, a partition for dividing the casing into compartments, wheel-buckets located in the compartments, a shaft for the wheels, fluid-discharging devices, and a wall carried by the partition and located between the casing and the shaft and in close proximity to the buckets for preventing currents of motive fluid from flowing across the surface of a wheel from one fluid-discharging device to another.

16. In an elastic-fluid turbine, the combination of a casing, a partition for dividing it into compartments, wheel-buckets located in the compartments, fluid-discharging devices which are angularly displaced around the wheel, and a cylindrical wall carried by the partition and situated between the casing and the shaft to form an annular chamber for the fluid exhausting from the wheel, the said wall also acting to prevent the fluid from flowing across the wheel from one discharging device to another.

In witness whereof I have hereunto set my hand this 22d day of September, 1904.

OSCAR JUNGGREN.
